[57] CLAIM

The ornamental design for a game board, as shown and described:

DESCRIPTION

FIG. 1 is a perspective view of a game board, showing my new design;

FIG. 2 is an enlarged top plan view thereof, the bottom being unadorned; and,

FIG. 3 is an enlarged side elevational view thereof, the other sides being identical.

The broken line showing of the indicia is for illustrative purposes only, and forms no part of the claimed design.

FIG. 1.

FIG. 3.

FIG. 2.
